UNITED STATES PATENT OFFICE

2,000,607

GAS CANNON

Edward Sutton Peake, Westerville, Ohio, assignor to The Kilgore Manufacturing Company, Westerville, Ohio, a corporation of Ohio

Application May 12, 1932, Serial No. 610,751

8 Claims. (Cl. 42—55)

My invention relates to gas cannons.

It is the object of my invention to provide a gas cannon using predetermined sized, formed ammunition delivered from a point exterior of the cannon into a gas forming chamber outside of the cannon.

It is a further object to provide means of firing the gas in the gas forming chamber and permitting the discharge of the gases thus formed by the explosion into the barrel of the cannon.

It is my object to provide in connection therewith a resilient ball projectile.

It is my object to provide a gravity feed of ammunition of predetermined size and strength which may be supplied in the form of pellets, blocks, bars, capsules or strips.

It is my object to provide both a gravity feed and a mechanical feed.

It is a further object to provide in combination with the cannon and a gas forming means and ammunition a projectile carrying an expelling charge and time fuse, the fuse being ignited by the flame from the gas explosion at the same time the gases of the explosion propel the projectile out of the gun so that at the end of the flight of the projectile the contents of the projectile will be propelled and expelled, permitting a figure to descend on a parachute, such figure being used in the projectile to protect the parachute during discharge.

In particular it is my object to provide a gas cannon in which pre-formed gas forming substance of uniform strength will be fed to the cannon and only one of such pre-formed means can be fed at a time so that an excess charge cannot be gotten into the cannon by mistake.

Referring to the drawings, Figure 1 is a top plan view of a mortar.

Figure 2 is a section on the line 2—2 of Figure 1.

Figure 3 is a section showing a modified form of ammunition and ammunition feeding means.

Figure 4 is a similar view showing a modified form of ammunition and ammunition feeding means.

Figure 5 is a detailed section through a modified form of firing means using a flint.

Figure 6 is a section through the mortar showing the use of a parachute projectile carrying a time fuse and expelling charge.

Figure 7 is a diagrammatic view of the cannon discharging the projectile and the projectile discharging the parachute.

Figure 8 is a perspective of the stick ammunition.

Figure 9 is a perspective of the strip ammunition.

Figure 10 is a section through the cannon showing a push button type of feed utilizing carbide pellets.

Figure 11 is a section through a form using a carbide stick from which the pellets can be broken off.

Figure 12 is a section on the line 12—12 of Figure 10.

Referring to the drawings, 1 is a base having side members 2 constituting supports for the mortar trunnions 3 which are adjustably locked to the side walls 2 by the set screws 4. It is preferred to have the mortar adjusted at an angle of approximately 60 degrees.

The mortar consists of a barrel 5 having a breech 6 with a gas aperture 7 opening directly beneath the projectile such as the rubber ball 8. The mortar is provided with a gas chamber 9 formed by the projecting side walls 10 of the mortar and a detachable arcuate breech block 11 retained by the locking sleeve 12 threaded on the mortar at 13 and sealed thereto by the gasket 14. It is desirable that this chamber 9 have a semi-circular bottom. Within the chamber is a supply of water 15 directly beneath the ammunition port 16 through which drops by gravity the ammunition pellets of gas forming material such as carbide, designated 17. These pellets are loaded into the chamber 13 within the sleeve 19 closed by the door 20. The bottom of the chamber 13 is controlled by the rotating valve member 21 which is slotted at 22 to form a pocket of sufficient size to receive one of the pellets 17. When this valve member is rotated to receive an ammunition pellet in the pocket 22, its wall 23 closes off the opening 16 and when the valve member 21 is again rotated to discharge the ammunition pellet through the opening 16, the rear wall 23 shuts off the passageway 18 so that only one ammunition pellet at a time can be discharged into the water 15. The valve member 21 is actuated by the thumb piece 24 and is limited in its rotation by the finger 25 and shoulder 25a.

When the carbide pellet 17 drops into the water, gas is formed. This gas may be fired by any desired means, such as by the hammer 26 actuating the firing pin 27, firing the cap 28 which communicates through the port 29 with the interior of the chamber 9 firing the gas charge, with the result that the gases are dis-

charged through the port 7 and propel the projectile 8 into the air. This hammer is held in either firing or inoperative position by the spring-pressed plunger 30 actuated by the spring 31 in the chamber 32. The plunger 30 has the roller 33 engaging the cam nose 34 on the trigger 26. The trigger 26 is pivoted at 35 on the ears 36 and is actuated by the lanyard 37.

Referring to the modification in Figure 5, it will be observed that in this case a flint is utilized comprising a firing pin 27 having a head 38 which is pressed backwardly by the spring 39 which carries with it the head 40 of the corrugated member 41 having the flint plunger 42 operating in the chamber 43 and pressed by the spring 44.

Referring to the modification as shown in Figure 3, it will be noted that in this case a bar of carbide designated 45 which is weakened along the lines 46 is pressed by the spring 47 under the screw top 48 downwardly through the chamber 18 in the ammunition container 19 in the path of the reciprocating plunger 49 which is adapted to shear the bar of ammunition 45 into blocks of equal size along the lines 46, discharging one block at a time into the water 15. The plunger 49 is pivoted at 50 to the actuating lever 51 which is pivoted at 52 on the ammunition container 19. This lever 51 is spring pressed by the spring 53 to hold it against the top of the bar of ammunition 45.

Referring to the modification in Figure 4, I have provided in this arrangement a strip of ammunition comprising a series of pellets 54 which are carried on a paper strip or between paper strips 55. This strip is fed over the ammunition opening 16 by the corrugated feed wheel 56 having teeth 57. This wheel is pivoted at 58 on the pivot of the actuating arm 51 which carries the pusher and shear member 49 that has a cutting edge 49a for shearing the paper strip 55 to release the pellet 54 so that it can drop in the water 15. Spring members 59 and 60 carry it respectively on the housing 19 and the lever 51, which serve to regulate the movement of the corrugated wheel 56. The ammunition strip is preferably wound on the carrier pin 55a.

Referring to the modification in Figure 6, where a projectile is used with a time fuse and expelling charge, I provide a cylindrical projectile 61 having an expelling charge 62 in the base with an oppositional cover 63 acting as a gas check and also as a support for the base 64 of the figure 65 which extends through to the upper end of the projectile beneath the cover 66. A parachute 67 is wrapped around the figure so that the entire thrust is on the figure and not upon the parachute. The parachute is attached to the figure by the parachute cords 68.

The expelling charge 62 is fired by the time fuse 69 which constitutes a powder charge compressed within the sleeve 70. This powder is exposed at 71 to the flame passing through the opening 7 upon the explosion of the carbide gas as heretofore described. The projectile is forced out of the gun by this explosion and the time fuse is ignited so that after the projectile reaches a predetermined height, the time fuse will burn through and ignite the expelling charge 62, blowing the figure and the parachute wrapped around it out of the projectile, enabling the parachute to come down open, with the thrust member such as the figure 65 being then used as the weight to draw the parachute back to earth.

Referring to Figure 10, it will be observed that I employ an ammunition chamber 19 to which there are fed a plurality of cylindrical pellets 72. Due to the angular position of the cannon, these pellets feed downwardly by gravity so that the bottom one rests against the bottom wall of the ammunition chamber 19 at 19a. Over this last pellet is a spring restricting plunger 73 held backwardly by the spring 74 which can be depressed by the finger piece 75 to drop the last or bottom pellet into the water 15. Upon the withdrawal of the plunger 73, the next succeeding pellet will drop into position for the feeding operation.

At the same time it will seal the discharge opening 16 through which the pellet has been delivered to the water 15. When the gas is generated, it makes its exit into the gun barrel 5 through the passageway 7 over the flint firing mechanism which is located in the cannon barrel 5.

This flint firing mechanism is designed and arranged as follows:

The lanyard 37 is adapted to pull back the pawl 76 upon the shoulder 77 on which the firing pin head 78 rests when the cannon is ready to fire. A spring 79 serves to move the head 78 with its firing pins 80 and ratchet firing member 81 over the exterior flint 82 and the interior flint 83. Springs 84 under heads 85 serve to move these flints against the ratchet surface of the member 81. As the carbide gas flows over the flint mechanism, it is fired so as to drive the rubber ball 8 or any other projectile out of the cannon.

In Figure 11 is shown a modified form of ammunition consisting of a carbide stick 86 weakened at intervals at 87 so that a pellet 88 can be broken off to drop into the water 15 and then the swinging cover 89 will close the discharge opening 16 and firing can take place. This stick may have a cover of thin paper, water-proof material, gelatin or the like to protect it before it is dumped into the water. These sticks 86 will be furnished to the trade in closed containers such as bottles so as to preserve the carbide. The advantage of this construction is that it eliminates special loading mechanism.

The stick 86 or the pellet 72 may have such a coating as described indicated at 90, which is shown partially broken away in Figure 11.

It will be further noted in connection with the member 81 that it is partially cut away at 81a to provide a vent. In non-firing position the member 81 closes the port 7 but in firing position it opens the port 7 to permit the carbide gas to flow into the gun barrel 5. This facilitates the firing by the notched steel member 81 striking against the flint. This arrangement permits the gas to be held in the generating chamber until the ball is placed in the end of the cannon. It eliminates escaping of the gas without functioning and there is no chance for the explosion traveling down into the generating chamber. This permits more carbide to be placed in the generating chamber than could be ordinarily placed therein as the gas flow will be governed to such an extent that the efficiency of the cannon will be greater than has been heretofore possible, as heretofore it has been impossible to control the gas flow.

According to my method, I prepare and supply a gas forming charge such as a pellet or block of carbide of known strength to a measured quantity of water, one pellet at a time,
